Inventor:

T. Clifford Bush

United States Patent Office.

T. CLIFFORD BUSH, OF NEW HAVEN, CONNECTICUT, ASSIGNOR TO HIMSELF, HENRY P. OSTRAM, AND T. B. CARPENTER, OF SAME PLACE.

Letters Patent No. 85,788, dated January 12, 1869.

TOY BLOW-GUN.

The Schedule referred to in these Letters Patent and making part of the same.

To all whom it may concern:

Be it known that I, T. CLIFFORD BUSH, of New Haven, county of New Haven, and State of Connecticut, have invented a new and useful Improvement in Toy Air-Guns; and I do hereby declare the following to be a full, clear, and exact description of the same, reference being had to the accompanying drawings, and to the letters of reference marked thereon.

Said drawings constitute part of this specification, and represent, in—

Figure 1, a side view of my improvement, and in

Figure 2, a longitudinal section of the same.

Similar letters of reference, when they occur in the separate views, indicate like parts.

My invention relates to an improved toy air-gun, and consists of a tube or barrel, placed upon a stock, and furnished at the breech with an aperture for the reception of the arrow or cartridge. Connecting with this barrel, at the breech, is placed a flexible tube, or its equivalent, which extends through a portion of the stock, and is furnished with a mouth-piece. After the arrow or cartridge has been placed in the barrel, the mouth is applied to the said mouth-piece, and, by the force of the breath, the arrow or cartridge is ejected from the barrel, and, by practice, may be thrown a considerable distance with great accuracy.

The object of my invention is to furnish a game for young people, which will be amusing, as well as beneficial to the health, by developing and expanding the lungs, and by otherwise benefiting the parties using it.

To enable others skilled in the art to make and use my invention, I will proceed to describe the construction and operation of the same.

A is a tube or barrel, which may be made from a piece of common gas-pipe, or other suitable material. This barrel is open at both ends, and in the upper side, near the breech, an aperture is formed sufficiently large to enable the arrow or cartridge to be placed in the said barrel.

B is a ferrule or slide, arranged to move upon the barrel A for the purpose of covering, when in use, the aperture in the same, and to prevent the escape of the air.

C is the shoulder-piece or stock, in which the barrel is held.

In the end of the said barrel, and extending down the centre of the stock, say one-third its length, then outward to the surface, a hole is bored. Through this said hole a flexible tube, D, or its equivalent, is passed, one end connecting with the end of the barrel, and the other, which extends beyond the stock to any length required, is furnished with a mouth-piece, E. The object of this tube is to bring the mouth-piece in the proper position for use when the head is bent forward for the purpose of taking aim.

This completes the construction of my improvement. The operation is as follows:

First, the ferrule or slide B is thrown forward to the position shown in red, fig. 1, and in black, fig. 2. The arrow or cartridge is then inserted into the barrel through this opening, as shown in red, fig. 2. After the arrow or cartridge has been thus placed in the barrel, the ferrule or slide is drawn back, as shown in red, fig. 2. This closes the barrel. The mouth is then applied to the mouth-piece E, and, by blowing through the tube D, the arrow or cartridge is carried from the barrel, and may be thrown to a greater or less distance, according to the force of the blast given from the lungs.

My gun may be aimed as well as other guns, and the arrow or cartridge thrown with great accuracy.

I do not confine myself to the use of the form of arrows shown in red, fig. 2, as a cartridge may be formed, made of any suitable material.

I do not broadly claim an air-gun for throwing the arrow or cartridge by the force of the breath, as such is not new.

What I do claim as new and useful, and desire to secure by Letters Patent, is—

The said gun, when furnished with a slide, B, stock C, and flexible tube D, or its equivalent, in the manner and for the purpose substantially as herein specified.

T. CLIFFORD BUSH.
